UNITED STATES PATENT OFFICE.

ARTHUR J. CUMNOCK, OF NEW YORK, N. Y.

METHOD FOR MAKING COLLARS.

1,073,080.

Specification of Letters Patent. Patented Sept. 9, 1913.

Continuation of application Serial No. 357,850, filed February 18, 1907. This application filed February 5, 1912. Serial No. 675,614.

To all whom it may concern:

Be it known that I, ARTHUR J. CUMNOCK, a citizen of the United States, residing at New York, in the county of New York and State of New York, have invented certain new and useful Improvements in Methods for Making Collars, of which the following is a specification.

This invention relates to a method of 10 making collars and similar articles and is a continuation of my pending application Ser. No. 357,850, filed February 18, 1907.

The method preferably concerns itself with making collars from tubular webs, the 15 web or fabric being provided with interwoven portions and a main feature of the invention consists in so weaving the fabric that articles having upper and lower edges of dissimilar contour may be cut therefrom 20 and to that end the interwoven portions are so spaced that the upper part of one article, such as a collar, and the lower part of another additional article of the same kind can be formed from the part between the in- 25 terwoven portions.

In the drawings: Figure 1 is a plan view of a portion of the fabric. Fig. 2 is a plan of a modification.

Like letters of reference indicate like 30 parts throughout the several drawings.

Referring to the drawings, A represents the fabric, which, in this instance, is a tubular seamless woven fabric, and the two layers of the fabric are indicated by B and 35 C. The interwoven portions of the tubular fabric are indicated by D, and, in Fig. 1, the portions D are woven transversely of the warp, while in Fig. 2 the interwoven portions, indicated by E, are preferably formed 40 unstaggered, extending in straight lines.

Referring to Fig. 1, it is apparent that the interwoven portions are so spaced that between two rows of interwoven portions there are shown parts of two different collars, to-wit: the upper fold of one collar and the lower fold of a second collar, the folds of the collar being indicated in dotted lines. The upper edges of one collar are of entirely dissimilar contour from the lower 45 edges of the other collar, and consequently by cutting the upper fold of one collar from the part of the fabric between two rows of interwoven portions there will be left the lower fold of another collar projecting beyond one interwoven portion.

The interwoven portion D in Fig. 1 and E in Fig. 2 are broken as indicated in the drawings instead of extending continuously, and one of the objects of breaking these portions is to enable the collars or other articles to be cut or otherwise formed out of the fabric around the broken interwoven portions so that each article shall have an interwoven portion embedded therein.

In order to facilitate the laying out of the collar or article to be cut the interwoven portions D or E preferably lie end to end in substantially parallel rows. In Fig. 1, the collars are indicated in the dotted lines F, 70 each collar being outlined around an interwoven portion D and, as shown, the interwoven portions are preferably arranged to comprise part of the collar band and the collar when cut out will have folds projecting above and below the interwoven portions and in order to save material and prevent waste the outlines of the collar are preferably nested as indicated in Fig. 1 and to this end the interwoven portions are also 75 staggered.

From the foregoing explanations it will be seen that the method comprises preferably a tubular fabric, but the main feature is in having upper and lower layers of fabric with interwoven portions and then arranging the interwoven portions so that parts of two collars will lie between the rows of interwoven portions and in cutting or forming the article, simultaneously cutting different parts of two articles of the same kind from the intermediate part lying between the interwoven portions.

Having thus described my invention, I claim:

1. The method of forming collars from a fabric by first weaving the fabric with rows of interwoven portions, the interwoven portions consisting of upper and lower layers of fabric woven together and strips of fabric arranged between the rows of interwoven fabric projecting beyond the interwoven portions in each direction, the width of said strips between the interwoven portions being sufficient to comprise the upper fold of one collar and the lower fold of a second collar and thereafter cutting the strip of fabric between the interwoven portions whereby there will be simultaneously 105 formed the upper fold of one collar and the 110

lower fold of another collar, substantially as specified.

2. The method of forming a collar from a tubular fabric by first interweaving together 5 portions of the upper and lower layers of said fabric and arranging sufficient material between the interwoven portions to comprehend both an upper and lower fold of a collar and thereafter forming the collar by 19 simultaneously cutting the upper fold of one collar and the lower fold of another collar

from the material between the interwoven portions by cutting along a line beyond the interwoven portions and intermediate two interwoven portions, substantially as specified. 15

In testimony whereof, I have hereunto set my hand this 30th day of January 1912.

ARTHUR J. CUMNOCK.
